UNITED STATES PATENT OFFICE.

EDWARD A. HALBLEIB, OF ROCHESTER, NEW YORK, ASSIGNOR TO NORTH EAST ELECTRIC COMPANY, OF ROCHESTER, NEW YORK, A CORPORATION OF NEW YORK.

POWER-TRANSMISSION MECHANISM.

1,119,151.

Specification of Letters Patent.

Patented Dec. 1, 1914.

Application filed November 6, 1913. Serial No. 799,599.

To all whom it may concern:

Be it known that I, EDWARD A. HALBLEIB, a citizen of the United States, and resident of Rochester, in the county of Monroe and State of New York, have invented certain new and useful Improvements in Power-Transmission Mechanism, of which the following is a specification.

This invention relates to mechanism for supporting and actuating an electric generator in connection with an internal-combustion engine.

The object of the invention is to produce an arrangement by which a generator may be connected with an automobile-engine and driven thereby, or used as a source of power to start the engine, without any substantial change in the construction or arrangement of the parts of the engine or of its accessories, and particularly with the generator located alongside the engine in the space usually available within the bonnet by which the engine is inclosed. To this end I employ an arrangement in which the generator is carried on a support mounted alongside the engine, and I connect the generator-shaft with the engine-shaft by means including a chain and sprocket wheels, and provide for the necessary adjustment of the tension of the chain by the novel means for that purpose hereinafter described.

Other objects and features of the invention will be set forth in connection with the following description of the preferred embodiment of the invention.

In the accompanying drawings:—Figure 1 is a front-elevation of power-transmission mechanism embodying the present invention; and Fig. 2 is a plan-view of the same, with the addition of a fan upon the counter-shaft.

The invention is shown as applied to the engine of a well-known type of automobile, the cylinders 5, the crank-case 6, the crank-shaft 7, and the gear-housing 8 of the engine being all of ordinary form. The drawings illustrate also a generator 9 of ordinary form, which is preferably adapted to operate also as a motor to start the engine, and is provided with the usual armature-shaft 10.

In the illustrated mechanism I employ a counter-shaft 11, through which the armature-shaft is connected with the crank-shaft of the engine. This counter-shaft is located above and parallel with the crank-shaft 7,

and is provided with a sprocket-wheel 12 from which a sprocket-chain 13 extends to a sprocket-wheel 14 fixed on the crank-shaft. A second sprocket-wheel 15 on the counter-shaft is connected, by a chain 16, with a sprocket-wheel 17 on the armature-shaft 10. These chains and sprocket-wheels afford a positive connection between the armature-shaft and the crank-shaft at all times, and the ratio of the diameters of the several sprocket-wheels is such as to make a speed-reduction between the generator and the crank-shaft, so that the generator may be driven at high speed when the engine is running, and may also apply its power effectively to start the engine.

The counter-shaft 11 is supported in bearings in a yoke 18, which is provided with an arm 19 pivoted upon a stud 20 projecting from the engine. This stud is one of the studs or screws normally employed to hold the cover of the gear-housing 8. The bearing-yoke 18 is thus supported by the stud 20, and as a further provision for the same end it has a depending arm 21, which carries an adjusting-screw 22 at its lower end, the lower end of the screw, in turn, bearing upon the head 23 of a screw conveniently located on the crank-case of the engine. The screw 22 supports the arm 21 and the bearing-yoke against the pull of the chain 13, but the tension of the chain may be adjusted, to take up slack, by turning the screw 22, which is then fixed in adjusted position by a lock-nut 24. To further support the bearing-yoke the arm 21 is provided with a slot 25 which receives a stud 26 screwed into the front of the crank-case of the engine. The slot 25 permits the arm 21 to swing about the stud 20 for the purpose of adjusting the chain 13, as just described, but the stud 26 steadies the arm against movement in a fore-and-aft direction.

The generator is carried by a support 27 having a concave seat, which fits the generator-casing, and depending arms which are mounted, at their lower ends, upon pivots 28 fixed in a base-member 29 screwed to the crank-case of the engine. The casing of the generator is generally-cylindrical in form, so that it may be turned in its seat on the support 27, but it is normally fixed thereon by means of a device comprising straps 30, fixed to the support, and connected at their 110

upper ends by a T-bolt 31. To provide for the adjustment of the chain 16 the generator-casing is provided with an integral arm 32, which has a slot 33 at its end, and this slot receives a stud 34 fixed in a forked arm 35 integral with the bearing-yoke 18. The slot 33 is eccentric to the axis of the generator-casing and also to the stud 20, and accordingly, when the bearing-yoke is moved about the stud to adjust the chain 13 the stud 34 and the slot 33 have a cam-action which causes a slight inward or outward swinging movement of the generator and its support, about the pivots 28, which results in the simultaneous adjustment of the chain 16. The adjusting-mechanism is designed to proportion the two simultaneous adjustments to the wear to which the chains are respectively subjected, and to permit this wear to be equalized the chains are made both of the same length and interchangeable, so that they may be interchanged occasionally. In setting up the apparatus in the first place, however, independent adjustment of the chains may be desirable, and this is provided for in the arrangement described, for, on loosening the T-bolt 31 the generator may be turned in its seat, thus swinging the slotted arm 32 with respect to the stud 34, and adjusting the chain 16 without any corresponding adjustment of the chain 13.

The counter-shaft 11 is arranged to occupy the position occupied normally by a belt-driven fan-shaft, and accordingly the counter-shaft may be utilized, in place of the usual fan-shaft, as a means for actuating the fan. In Fig. 2 a fan 36 is shown as mounted upon the forward end of the counter-shaft. The sprocket-wheel 14 and the chain 13 also occupy the positions usually occupied by a pulley and a belt, respectively, for driving the fan, while the generator and its support occupy positions within the bonnet of the automobile which are normally vacant. For these reasons, and for the further reason that the various studs and screws employed to support the mechanism are merely substituted for those already found in similar positions, it will be apparent that the present mechanism is adapted for convenient application to an automobile of ordinary construction, without any substantial change in the construction or arrangement of its parts, while the generator is also located in a position where it is conveniently accessible for inspection or repair.

In an arrangement such as that described the chains are sometimes subjected to heavy tension, when the direction of rotation of the armature-shaft is suddenly reversed in consequence of a back-kick in the engine. In the present arrangement, however, notwithstanding the fact that all of the parts

are relatively movable for the purpose of adjusting them to fit various engines and to take up slack in the chains, such tension is rigidly resisted, for the bearing-yoke, with its three integral arms, constitutes, in effect, a rigid triangle having three points of support, at the ends of its three arms, which prevent movements either in, or transverse to, its plane.

My invention is not limited to the embodiment thereof hereinbefore described and illustrated in the accompanying drawings, but it may be embodied in various other forms within the nature of the invention as it is defined in the following claims.

I claim:

1. In combination with an engine; a generator located alongside the engine; a support in which the generator is rotatably mounted; means, including sprocket-wheels and a chain, connecting the generator-shaft and the engine-shaft; means connected with, and operable by rotation of, the generator for adjusting the tension of said chain; and means for normally preventing such rotation of the generator in its support.

2. In combination with an engine, and a counter-shaft located above the engine-shaft and rotatably connected therewith; a generator-support pivoted to one side of the engine and extending upwardly; a generator supported thereby and rotatable thereon; means normally preventing rotative movement of the generator with respect to the support; sprocket-wheels and a chain connecting the counter-shaft and the generator-shaft; and means connecting the generator and the engine to normally prevent movement of the generator-support, said means being adjustable, by a partial rotation of the generator on the support, to vary the distance between the generator-shaft and the counter-shaft and adjust the tension of said chain.

3. In combination with an engine, and a counter-shaft located above the engine-shaft and rotatably connected therewith; a bearing-member on which the counter-shaft is supported; a generator-support pivoted to the side of the engine and extending upwardly, the support being provided with a concave seat; a generator, having a casing of circular form, mounted on said seat; sprocket-wheels and a chain connecting the counter-shaft and the generator-shaft; means normally preventing rotative movement of the generator-casing in said seat; and pin-and-slot connections, between the generator-casing and the bearing-member for the counter-shaft, arranged to adjust the distance between the counter-shaft and the generator-shaft when the generator is turned in its seat on the support.

4. In combination with an engine; a counter-shaft located above the engine-shaft; a

- bearing-member for the counter-shaft pivotally mounted on the engine and provided with two arms; an adjusting-screw in one of said arms engaging the engine and adapted 5 to swing the arm and the bearing-member about the pivotal mounting; sprocket-wheels and a chain connecting the counter-shaft and the engine-shaft and adjustable by the action of said screw; a generator; means 10 for supporting the generator alongside the engine, said means being adapted to permit movement of the generator toward and from the engine; sprocket-wheels and a chain connecting the counter-shaft 15 and the generator-shaft; and means normally preventing said movement of the generator but adjustable to vary the distance between the generator and the counter-shaft and adjust the tension of the last-men 20 tioned chain.
5. In combination with an engine; a counter-shaft located above the engine-shaft; a generator located alongside the engine and the counter-shaft; sprocket-wheels and 25 chains connecting the engine-shaft with the counter-shaft and the counter-shaft with the generator-shaft; means for moving the counter-shaft upwardly to adjust the tension of one chain; and means for moving the generator outwardly from the engine to adjust, 30 independently, the tension of the other chain.
6. In combination with an engine; a counter-shaft located above the engine-shaft; a generator located alongside the engine; sprocket-wheels and chains connecting the counter-shaft with the engine-shaft and the generator-shaft, respectively; a bearing- 35 member, for the counter-shaft, movable toward and from the engine-shaft to adjust one of said chains; and means for supporting the generator and connecting it with said bearing-member, said means being adjustable to move the generator toward and 40 from the counter-shaft and adjust the other chain.
7. In combination with an engine; a counter-shaft located above the engine-shaft; a generator located alongside the engine; sprocket-wheels and chains connecting the counter-shaft with the engine-shaft and the generator-shaft, respectively; and a bearing-member, for the counter-shaft; connected 45 with the engine and the generator and movable, relatively thereto, in a direction to tighten both chains simultaneously.
8. In combination with an engine; a coun- 50 ter-shaft located above the engine-shaft; a generator located at one side of the engine and the counter-shaft; a pivot, on the engine, at the opposite side of the counter-shaft; a bearing-member for the counter-shaft, having two laterally-projecting arms connected, respectively, with the pivot and the generator; sprocket-wheels and chains 55 connecting the counter-shaft with the generator-shaft and the engine-shaft, respectively; and means for rocking the bearing-member in a vertical plane to adjust the chain connecting the counter-shaft with the engine-shaft.
9. In combination with an engine; a counter-shaft located above the engine-shaft; a generator located at one side of the engine; a generator-support pivoted to the engine; a bearing-member, for the counter-shaft, pivoted to the engine and movably connected to the generator-support; sprocket-wheels and chains connecting the counter-shaft with the generator-shaft and the engine-shaft, respectively; and means for fixing the bearing-member normally against pivotal movement.
10. In combination with an engine; a counter-shaft located above the engine-shaft; a generator located alongside the engine; a generator-support connected to the engine at one side thereof; sprocket-wheels and chains connecting the counter-shaft with the engine-shaft and the generator-shaft, respectively; and a bearing-member, for the counter-shaft, connected with and supported by the generator-support but movable, relatively thereto, in a direction to adjust the chain connecting the counter-shaft with the engine-shaft.
11. In combination with an engine; a counter-shaft located above the engine-shaft; a generator located alongside the engine; sprocket-wheels and chains connecting the counter-shaft with the engine-shaft and the generator-shaft, respectively; and a bearing-member, for the counter-shaft, having a laterally-projecting arm pivoted to the engine, and a vertically-projecting arm fixed, against both vertical and horizontal movement, by engagement with the engine; said bearing-member being adjustable, in a vertical plane, to adjust the tension of the chain connecting the counter-shaft with the engine-shaft.
